UNITED STATES PATENT OFFICE.

SVEN T. NELSON, OF MICHIGAN CITY, INDIANA, ASSIGNOR TO SULLIVAN MACHINERY COMPANY, A CORPORATION OF MASSACHUSETTS.

METAL-WORKING MACHINE.

Application filed June 18, 1921. Serial No. 478,498.

My invention relates to metal working machines and particularly to metal working machines of a type suited for the sharpening of mining machine bits.

5 An object of my invention is to provide an improved metal working machine. Another object of my invention is to provide an improved machine for sharpening mining machine bits. Other objects of my invention will appear in the course of the following specification and appended claims.

In the accompanying drawings I have shown for purposes of illustration one embodiment which my invention may assume 15 in practice.

In these drawings,

Fig. 1 is a side elevation, with parts broken away, of a bit sharpening machine embodying the illustrative form of my invention.

Fig. 2 is an enlarged view, partially in elevation, and in section through the centers of the dies of my improved mechanism.

Fig. 3 is a transverse section on the line 25 3—3 of Fig. 2, parts being shown in elevation.

For purposes of illustration I have shown my bit sharpening mechanism operated by a moving ram of the type which is common 30 in shapers. In this mechanism, the ram 1 is caused to reciprocate in guides 2 by means of an oscillating arm 3 pivoted at 4 and caused to oscillate by an adjustable crank pin 5, the adjustment being made by means 35 of a mechanism 6 of a well-known form which as disclosed is of the well-known Whitworth quick return motion mechanism.

Carried by the ram 1 is a roller die 7 which is formed in its periphery with a 40 groove 8 of such shape that its trace on a plane cutting the axis of the roller is the same as the transverse section on a vertical plane through the outer end of the drill bit formed thereby while the latter is in the sharpener (see Fig. 3). This roller is 45 adapted to cooperate with a stationary die block 9 which is provided with a shoulder 10 having an abutment die surface 11 against which the point of the bit is adapted to be 50 rested and to be formed. The block 9 is provided with a slot 12 extending there- 55 through at an angle and adapted to receive a bit (indicated in construction at 13 in Fig. 2) for re-sharpening. The distance which the bit 13 protrudes above the block

9 is regulated by a sliding wedge 14 which is adjustable by means of a stationary screw 15 and nut 16, the nut being rigidly secured to the wedge member 14 and the screw being rotated by a hand wheel 17. The abutment member 10 has sloping sides and a narrow top or upper end. A transverse section through the abutment member 10 is the same as the contour of the groove 8 and accordingly, as the ram 1 reciprocates, the abutment member 10 will be overrun by the roller 7 and the groove 8 will pass over the abutment member 10, engaging both the lateral surfaces and the top or upper end thereof.

From the foregoing description, the mode of operation of my improved mechanism will be readily apparent. A bit heated to the proper temperature will be drooped into the slot 12 and the wedge 14 adjusted by means of the screw 15 and nut 16 so that the bit protrudes slightly above the upper side of the abutment member 10. The ram 1 will then be caused to reciprocate and upon its forward or right hand stroke (see Fig. 1) will force over the metal of the heated bit against the surface 11 and will form the bit into approximately proper contour. In the event that the bit did not protrude a sufficient amount from the slot 12 to fill out the outer end of the bit to the desired proportions, the wedge 14 will be again adjusted so that the heated blank or bit is forced up slightly further whereupon the rolling action is repeated. When the sharpening of the bit has progressed to such a point that the bit is of the proper contour and completely fills up the space between the path of the roller and the surface 11, the bit will be withdrawn and will be ready for tempering. The fact that the socket 12 is disposed at some such angle as shown is of great importance in the production of proper bits. This angle will be so selected that the angle between the shank of the bit and a vertical line during sharpening will be greater than the angle between the shank and a line perpendicular to the instantaneous path of movement of the bit during cutting. By virtue of this arrangement, when the shank of the sharpened bit is secured in a link of a cutter chain the front surface of the cutting end will be wider than the stock which supports it, and so there will be no wedging at the sides of the

bit and no friction, but instead the cutting edge of the bit will clear a path in which the bit will run clear.

To prevent injury to the bit by the unyielding impact of the die 7 thereon upon return movements of the latter, I provide means, herein of the clapper-box type of construction, as indicated at 18 to permit the die to lift in case it engages the bit while moving on its return stroke.

In forging cutter bits it is of course highly desirable to forge the same while hot as rapidly as possible. This is accomplished by the use of the quick return motion mechanism which will give a greater number of forging strokes for a unit of time than if the ram was reciprocated at a uniform rate of speed in each direction. The ram on the forging stroke need only travel at its normal forging speed while the ram speed on the return stroke would be greater to thereby give the greater number of strokes per unit of time. A further advantage derived is that the forging roller will be more apt to be given a spinning action on its rearward stroke due to the quick return and in that way cause a new portion of the forging surface of the roller die to be presented to the bit on each succeeding stroke. This not only insures more even wear of the walls of the roller die groove, but also in case of an irregularly worn roller, or foreign material being carried on the walls of the groove, the worn portion or foreign matter will not on each succeeding stroke be brought in contact with the identical portion of the surface of the bit as it was previously in contact with for the spinning action of the roller will present, as before stated, a new portion of the forging surface. Thus the bit portion will be more perfectly formed, even in spite of an irregularly worn roller or the presence of foreign matter.

While I have in this application specifically described one form which my invention may assume in practice, it will be understood that this form of the same is for purposes of illustration and that the invention may be modified and embodied in various other forms without departing from its spirit or the scope of the appended claims.

What I claim as new and desire to secure by Letters Patent is:

1. In a forging machine for forming cutting ends on tools, a rotatable forming die provided with a peripheral groove of uniform cross section, an abutment against which the blank lies during forging, and means for causing relative movement between said rotatable die and said abutment in such manner that during at least a part of said movement the abutment is within the groove.

2. A forging machine for forming cutting ends on tools comprising die means for

forming the lateral surfaces of a tool, a die which interfits with said first mentioned die means, means for supporting a tool for engagement by said dies during the forging operation, and means for causing relative movement between the dies.

3. In a bit forming device, a blank carrier member, a die associated therewith forming an abutment against which a blank may rest, a rotatable forming die having a peripheral groove of uniform cross section throughout its length but of a greater width at the periphery of the die than the bottom of the groove, said abutment substantially fitting said groove, and means for causing relative bodily movement between said carrier member and said rotatable forming die.

4. In a bit forming device, a blank carrier member including a die forming an abutment against which a blank may rest, a rotatable forming die having a peripheral groove of a greater width at the periphery of the die than the bottom of the groove, said abutment substantially fitting said groove, and means for causing relative bodily movement between said carrier member and said rotatable forming die.

5. In a bit forming device, a blank carrier member having a die surface formed thereon, a freely rotatable forming die provided with a peripheral groove to form the cutting portion of said bit, and means for effecting relative movement of said member and said die whereby a blank carried by said carrier may be subjected to the action of said die.

6. In a bit forming device, a blank carrier member having a die formed thereon, a grooved rotatable forming die adapted to cooperate therewith, said first mentioned die conforming in transverse section to the shape of said groove, and means for causing relative movement of said member and said rotatable die whereby a blank carried by said carrier may be subjected to the combined action of said dies.

7. In a bit forming device, a blank carrier member having a die disposed thereon and provided with a blank receiving slot, a rotatable forming die adapted to cooperate therewith, and means cooperating with said member to prevent the insertion of a blank in said slot beyond a predetermined point and to vary the depth to which said blank can be inserted therein, said means maintaining its cooperating position during operation of the forming die.

8. In a bit forming device, a blank carrier member having a raised die associated therewith and provided with an upper end and side surfaces, means comprising a rotatable forming die, and means for causing relative movement between said member and rotatable die whereby a blank carried by said carrier may be subjected to the action of said

rotatable die, the movement of said rotatable forming die causing the periphery thereof to roll substantially in contact with the upper end and side surfaces of said die on the relative movements of the parts.

9. In a bit forming device, a reciprocating die carrier, a rotary die carried thereby, means for supporting a blank in position to be acted upon by said rotary die, said supporting means including means for adjusting the blank relative to the path of reciprocation of said die, and an upstanding abutment adapted to shape the front face of the bit by resisting the flow of metal during forging.

10. A forging machine for forming cutting ends on tools comprising a die against which the front face of the tool is to be formed and freely rotatable die means for forming the other bounding surfaces of the cutting end by directly engaging the same, and means for causing relative movement between said die and die means to effect forming of said cutting ends.

11. A forging machine for forming cutting ends on tools comprising a die to support the front face of the tool and die means for forming the lateral surfaces thereof with which said first mentioned die inter-fits, and means for causing relative movement between said die and die means to effect forming of a cutting end.

12. A forging machine for forming cutting ends on tools comprising a die for supporting the cutting end of the tool and die means including surfaces operative to form the lateral surfaces of the cutting end, and means for effecting rectilinear relative movement between said die and die means in which the path of relative movement during engagement of the die surfaces with the cutting end intersects at an angle the axis of the shank of the tool extended.

13. In a bit forming device, a stationary blank carrier member, a rotary die and a carrier member therefor reciprocable relative to said blank carrier member, and means associated with said blank carrier member for the reception of a bit blank and for its adjustment relative to the path of movement of said rotary die carrier member including a wedge member disposed in the vertical plane in which the relative movement between said members takes place.

14. In a bit forming device, a stationary blank carrier member, a rotary die and a carrier member therefor reciprocable relative to said blank carrier member, and means associated with said blank carrier member for the reception of the blank and for its adjustment relative to the path of movement of said rotary die carrier member including a wedge member reciprocable in a groove in said blank carrier member.

15. In a bit forming mechanism, a blank

carrying member including a die adapted to support and form the point of a bit, a freely rotating grooved die adapted to cooperate therewith to form the sides of the bit by directly engaging the same, and means for moving said last mentioned die towards and past said other die in a direction so that it overruns said point last.

16. In a bit forming mechanism, a blank carrying member including a die adapted to support and form the point of a bit, a freely rotating grooved die adapted to cooperate therewith to form the sides of the bit portion by directly engaging the same, and means for moving said last mentioned die towards and past said other die in a direction so that it overruns said point last, said die moving means including a pivoted support for said second mentioned die permitting the same to yield if said die engages said blank when moving in the opposite direction to that specified.

17. In a bit forming device, a blank carrier having a blank receiving slot therein, and a member disposed below said slot and movable transversely of the shank of the blank, said member having an inclined face against which the shank end of the blank abuts and on which it rests by gravity.

18. In a bit forming device, a blank carrier having a blank receiving slot therein, and a member disposed below said slot and having an inclined face against which the shank end of the blank abuts, said member being movable transversely of the shank axis to vary the depth to which a blank can be inserted in said slot.

19. A forging machine for forming the cutting ends of tools comprising relatively movable blank supporting and die forming members, the latter being operative to form the lateral surfaces of said cutting ends by direct engagement therewith, and means for feeding the tool.

20. A forging machine for forming the cutting ends of tools comprising relatively movable blank supporting and die forming members, said members cooperating to form all of the bounding surfaces of the cutting end of a tool, and the former including an abutment against which the cutting end of the tool rests while the latter has portions providing forming surfaces movable during engagement with the tool and is operative to form the lateral surfaces of the cutting end of the tool by direct engagement therewith of the forming surfaces.

21. A mechanism as set forth in claim 20 having means for effecting reciprocable relative movement between the blank supporting and die forming members.

22. A forging machine for forming the cutting ends of tools comprising relatively movable blank supporting and die forming members, the latter being operative to form

the lateral surfaces of said cutting ends by direct engagement therewith of the movable portion of the die members, and means whereby the path of relative movement at the instant of die engagement with the blank is at an acute angle to the direction of the longitudinal dimension of the blank as supported in said blank supporting member.

23. A machine for forming the cutting ends of bits comprising a freely rotatable forming die provided with a peripheral groove of uniform tapering cross section to form the lateral sides of a bit, a clapper box to rotatably support said die, a carrier in which the bit blank to be formed is supported, and means for moving the forming die relative to the carrier.

24. A bit forming machine comprising a bit carrier having a blank receiving slot therein, means disposed below said slot and movable transversely thereof for feeding said blank during forging thereof, and screw operated means for adjusting said latter means.

25. As an article of manufacture, a die for forming the cutting portion of a bit comprising a base portion, a die portion proper projecting therefrom and which has a transverse section conforming substantially to that of the cutting portion of a bit formed thereon.

26. As an article of manufacture, a bit forming die comprising a base adapted to be positioned in a suitable supporting member, said die having a die portion proper projecting therefrom and whose cross section is substantially the same as that of the cutting portion of a bit formed thereon, said die portion also having an inclined surface against which the cutting face of a bit formed thereon rests during forming.

27. As an article of manufacture, a bit forming die comprising supporting and raised die portions, said latter portion being adapted to cooperate with a suitable die forming roller to form the cutting end of a bit.

28. As an article of manufacture, a bit forming die comprising a base, a die portion proper projecting therefrom and whose transverse section is substantially equal to the transverse section of the cutting portion of a bit formed thereon, said die portion having uniform sides along its longitudinal axis, and a plurality of angularly disposed surfaces, one of which is formed on the base and the other on the die portion.

29. A bit forming device comprising a member having a recess therein disposed at an angle to the vertical, a die carried by said member having a die portion proper projecting therefrom, said portion having a face inclined to the axis of said slot and having its transverse section substantially identical to the transverse section of the

cutting portion of the bit formed thereon, and a grooved roller cooperating with said die, the sides of said groove having substantially the same conformation as the sides of said die.

30. A bit forming device comprising a member having a recess therein disposed at an angle to the vertical, a die carried by said member having a die portion proper projecting therefrom, said portion having a face inclined to the axis of said slot and having its transverse section substantially identical to the transverse section of the cutting portion of the bit formed thereon, a grooved roller cooperating with said die, the sides of said groove having substantially the same conformation as the sides of said die, and means disposed below said slot to force a bit blank disposed therein outwardly therefrom.

31. A bit forming device comprising a roller die having a uniform groove therein around the periphery thereof, means for moving said roller die in a predetermined path, a member having a bit receiving slot therein disposed at an angle to the path of said roller, and a stationary die associated with said member and having a die portion proper projecting from said member and whose cross section is substantially the same as the cross section of said groove.

32. A bit forming device comprising a roller die having a uniform groove therein around the periphery thereof, means for moving said roller die in a predetermined path, a member having a bit receiving slot therein disposed at an angle to the path of said roller, and a stationary die carried by said member and having a die portion proper projecting upwardly from said member and whose cross section is substantially the same as the cross section of said groove, said die portion proper having a face against which a bit rests during forming thereon, said die face being disposed at an angle to the longitudinal axis of said slot.

33. In a forging machine, a blank support, a die member associated therewith against which rests the face of the cutting portion of a bit to be forged, a forging die having means providing a groove the walls of which directly engage the lateral surfaces of said bit cutting portion during forging thereof, and means for effecting relative reciprocatory movement between said face and die.

34. A forging machine comprising a blank support, a die against which rests the face of the cutting portion of a bit during forging thereof, a forging die having means providing a groove the walls of which directly engage and conform to the lateral surfaces of said cutting portion during forging thereof, and means for effecting relative reciprocatory movement between said support and die, the grooved portion of said die being

adapted to pass beyond the surface against which the bit face rests.

35. A cutter bit forging machine comprising a roller die, a cutter bit support, and means for causing relative reciprocable movement therebetween including mechanism operative on movement of one element thereof at a predetermined constant rate to effect the relative reciprocable movement aforesaid in one direction at a greater rate than that in the other direction.

36. A forging machine comprising a die, a stationary cutter bit support, and means for moving said die including mechanism operative automatically on the effecting of movement at a predetermined constant rate of one of its elements to effect one stroke of the die at a different rate of speed than the other thereof.

37. A cutter bit forging machine comprising a freely rotatable and reciprocable forging die, and means whereby said die will have a greater tendency to spin in one direction of reciprocation than in the other including die reciprocating mechanism operative on movement of one element thereof at a predetermined constant speed to effect a varying rate of die movement.

38. A cutter bit forging machine comprising a reciprocable forging die, and means for moving the same in different time periods through opposite movements of a single cycle of operation including means for positively moving the same in opposite directions including mechanism having an actuating element whose rate of movement is constant throughout the cycle.

39. In a cutter bit sharpening machine, a bit blank holder, a die movable relative to said holder to forge the cutting portion of a bit, and means for supporting said die comprising a pivoted clapper box.

40. In a forging machine, a die comprising a roller having a groove on the periphery thereof, a raised die cooperating with the groove in said roller die, and means for effecting relative movement between said dies.

41. In a forging machine, a grooved forming die movable in a predetermined fixed path throughout all forging operations, a stationary raised die formed to extend within the groove in said movable forming die and adapted to act as a rest against which a portion of the blank to be formed is held, and means for effecting movement of said movable forming die relative to said stationary die.

42. In a forging machine, a grooved roller die member movable in a predetermined fixed path throughout all forging operations, a supplemental stationary die formed to extend into the groove in said roller die and adapted to form a rest against which the portion of the blank to be formed is held, and means for effecting movement of said die relative to said stationary die.

43. In a forging machine, a crosshead member movable in a predetermined fixed path throughout all forging operations, a member pivotally connected to said crosshead member, a grooved roller die carried by said pivoted member, a supplemental stationary die member, and means for effecting reciprocation of said crosshead member.

44. In a forging machine, a stationary blank carrier member, a rotatable forging die member adapted to shape the sides of the blank movable in a fixed linear path throughout its entire forging operation, a die having outline supplemental to the shape of the rotatable die member carried by said carrier member, and means for effecting movement of said rotatable die.

45. In a forging machine, a forming die having a groove therein, a supplemental raised die formed to extend within the groove in said forming die, and adapted substantially completely to fill the section of the groove occupied thereby in a predetermined relative position of said dies, and means for effecting relative movement between said dies.

46. As an article of manufacture, for use in a forging machine, in which cutting tools are formed by the coaction of cooperating dies between which relative movement and an interfitting relation takes place during the course of a forging operation, a die element rotatable during the forging operation and having a forging groove of substantially uniform cross section extending completely around its periphery, said groove having a cross section which corresponds to the shape of the die with which said die element is adapted to interfit.

47. As an article of manufacture, a die for use in forming the cutting portion of a bit comprising a portion having a transverse section conforming substantially to that of the cutting portion of a bit formed thereon and having a surface providing a support for forming one surface of the bit forged.

In testimony whereof I affix my signature.
SVEN T. NELSON.
